CASTING FURNACES

Robert H. Ruppel, Granite City, Ill., and Charles E. Winters, Oak Ridge, Tenn., assignors to the United States of America as represented by the United States Atomic Energy Commission

Filed July 10, 1945, Ser. No. 604,278

3 Claims. (Cl. 22—73)

This invention relates generally to electric furnaces, and more particularly to a vacuum billet-casting furnace of the induction type for recasting uranium and/or other heavy metals, said furnace being constructed to eliminate "pipes" in the billet which form during cooling.

For use in neutronic reactors of the kind disclosed in Fermi et al. Patent 2,708,656, dated May 17, 1955, uranium and/or other heavy metals should be of great purity in order to obtain a high reproduction ratio. Therefore, it is very important to purify cast uranium of impurities, particularly of those with high "danger coefficients," as they are found in the so-called "biscuits" of uranium produced by reaction of UF_4 and magnesium.

In the past, it has been possible to produce billets of uranium, but not in the amounts and size necessary nor in a form suitable for rolling and fabrication into slugs for neutronic reactors. The biscuits as formed in the above process have traces of slag, magnesium and lime. In addition, "pipes" are formed in the billets during cooling which pipes preclude the rolling of the billets into slugs suitable for neutronic reactors.

The present invention is concerned with overcoming the above difficulties and has for a principal object the provision of an induction furnace for remelting and recasting in vacuum uranium and/or other heavy metals in large quantities into billets of pure metal which are free from shrinkage holes formed during cooling.

Another object of this invention is to provide an apparatus for casting metallic ingots relatively free from blow-holes, slag particles and non-metallic inclusions.

As will hereinafter appear, the objects are accomplished by providing a vacuum casting furnace comprising a melting furnace and a casting apparatus in combination. The furnace of this invention operates within the commercial range of frequencies from 60 cycles and upwards and may, therefore, be termed a high-frequency vacuum induction furnace.

In furnaces of the vacuum induction type, the electromagnetic fields produced in the vicinity of the furnace have a detrimental heating effect on the enclosing casing and, also, on the magnetic materials such as iron or steel in the vicinity of the furnace. To overcome these effects, it is proposed to install a water-cooled shell.

Other objects and advantages of the present invention will be more readily understood from the following description read with reference to the attached drawings wherein like reference characters indicate the same or similar parts:

Fig. 1 is a vertical cross-sectional view partly in elevation, on the line 1—1 of Fig. 2, illustrating a vacuum casting furnace constructed in accordance with the teachings of the present invention;

Fig. 2 is a top plan view of the vacuum casting furnace shown in Fig. 1;

Fig. 3 is a vertical cross-sectional view, partly in elevation, on the line 3—3 of Fig. 2;

Fig. 4 is an enlarged plan view of the rotatable mold table;

Fig. 5 is a plan view of the graphite melting crucible, part of the top being broken away for clarity; and

2

Fig. 6 is a vertical cross-sectional view, partly in elevation, on the line 6—6 of Fig. 5, showing the protective guide for the graphite plug for controlling the flow of molten metal from the crucible.

Referring to Figs. 1 and 2, a vacuum casting furnace 10, which is approximately 3 feet in diameter and 5 feet high, is supported above the floor at a convenient height for the removal of cast billets, on angle iron leg supports 11 welded to the steel bottom shell 12 of the furnace. 15 The main cylindrical shell 13 of the furnace 10 is welded to the bottom shell as indicated at 14. A grooved steel supporting ring 15 is welded to the main cylindrical shell at the top which supports a water-jacketed cover 16. At one side of the main cylindrical shell 13 and at the bottom thereof is an outwardly flanged manhole opening 17 for the insertion and removal of billet molds 18, which will be described later in detail in the description of the operation of the vacuum casting furnace. The flange of the manhole opening 17 is provided with a grooved supporting ring 19 to which is secured a removable cover 20. The cover 20 is connected to a bracket 23 which is pivotally connected to a support arm 21 pivotally mounted at its other end on brackets 22 welded to the cylindrical shell 12. The cover 20 is securely clamped to the ring 19 through clamping brackets 24 affixed to the cover 20 and clamping bolts 25 pivotally supported on the supporting ring 19. With this construction containing a gasket 26, it is evident, a vacuum-tight seal is provided between the cover 20 and the shell 13, and a closure is formed which may be readily opened for the insertion and removal of the billet molds 18.

In the bottom shell 12 is another flanged manhole 27 which is provided with a water jacket 28 and with couplings as shown for the attachment of piping from a cooling system. Suitably attached to the manhole opening 27 in a vacuum-tight relationship is a Bakelite cover 29. The Bakelite cover 29 supports water cooled bushings 30, to which is connected a water cooled conductor 31 for the helical induction coil 32 for heating the metal to be melted within a crucible construction, which, with the heating coil, is described in detail below.

Also supported by the bottom shell 12 of the furnace is a rotating mold table construction 33. The mold table construction 33 is mounted for rotary movement in a flanged bracket 34 forming a vacuum tight joint with an annular flanged member 35 suitably affixed to the under side of shell 12. The mold table 33 is supported on a vertical shaft 36 suitably journaled in the bracket 34 and provided with vertical adjustment by a collar 37. The collar 37 is provided with a set screw for securing the shaft 36 in its vertically adjusted position. A vacuum tight seal is provided for the support bracket 34 and the shaft 36 in the form of a suitable packing gland (not shown) affixed to the bracket 34 about the circumference of the shaft 36 and in the annular space formed between the shaft and the bracket 34. A hand wheel 38 is affixed to the shaft 36 to rotate the mold table 33 as successive molds 18 are poured. The mold table 33 is provided with a chamber 39 so that it may be water cooled. Water is admitted through the inlet piping 40, passed through holes 41 into the chamber 39, and discharged from the chamber 39 through the annular space 42 provided between the inlet pipe 40 and the shaft 36 and through outlet 43.

Steel supporting brackets 44 are affixed to the interior of the shell 13 on a level with the top of the manhole opening 17 to provide a support for a circular "Transite" compressed asbestos supporting member 45 which supports a crucible construction to be described later. The diameter of the supporting member 45 is less than the inside diameter of the shell 13 to provide an annular space for a cooling coil construction 46 and also to provide a passage to the bottom portion of the furnace so that the

furnace may be thoroughly evacuated. The cooling coil construction 46 extends from the bottom of the supporting member 45 to the top of the shell 13 where it is affixed to the supporting ring 15. The cooling coil construction 46 is formed from copper pipe flattened to the shape illustrated in Fig. 1 and helically coiled to fit the interior of the shell 13 with a spacing between the coils of substantially $\frac{1}{4}$ inch. The coil construction 46 is soldered to the shell 13 in heat conducting relationship. Referring to Fig. 2, the cooling coil connections for the inlet and outlet extend through the shell as at 47 and 48 connecting to a suitable supply of coolant. A copper band 49 may be soldered to the tubes to provide suitable support.

A sighting glass construction 50 is provided, as illustrated in Figs. 1 and 2, for viewing the pouring of the molten metal into the ingot molds 18. A hole 51 is provided through the "Transite" support 45 in the line of sight 52 (dotted line) between the sighting device 50 and the top of the mold 18.

A vacuum exhaust connection 53 of suitable size is provided for connecting the vacuum furnace in a suitable system for continuously evacuating the furnace to the vacuum desired. A manometer may be connected at 54 for determining the amount of vacuum in the furnace.

The water jacketed cover 16 is provided with a water chamber 55 formed by outer and inner dished shells 56 and 57, respectively, welded to a ring 58 adapted to fit into an annular slot 59 provided in the supporting ring 15. Water inlet and outlet connections are provided at 60 and 61, respectively. The outlet connection 61 acts as a centering pin for the cover 16 and is formed by a pipe connected through the outer dish shell 56, as illustrated in Figs. 1 and 2. A lifting connection 62 in the form of an inverted U-bolt bolted to the cover 16, as illustrated, is provided for the removal and replacement of the cover of the vacuum casting furnace when it is desired to load an enclosed melting crucible 63 after each heating.

A sighting glass 64 is provided for viewing the melting operation from time to time. The cover 16 is provided with suitable centering lugs 66 which work in conjunction with a centering pin 67 and the outlet connection 61 for aligning the cover. A vacuum tight joint between the cover 16 and the shell 13 is provided by a suitable gasket therebetween.

The cover 16 is provided with a bracket construction 68 pivotally supporting a lever 69 pivotally connected for vertically reciprocating a stopper rod 70 for actuating a graphite rod 71 which serves to open and close a hole 72 in the bottom of the crucible 63, Figs. 5 and 6. The rod 70 is mounted for reciprocation within a vacuum tight construction provided by the member 73 and the packing gland 74 forming a vacuum tight seal. The rod 70 is pivotally connected at its upper end to the lever 69 by an intermediate toggle member 75 and at its lower end to the graphite rod 71 through a member 76 which provides for the replacement of the graphite rod 71. A weight 77 is hung at the outer end of the lever 69 for biasing the graphite rod 71 to a position to effectively seal the opening 72 of the crucible 63. The other end of the lever 69 has pivoted thereto a downwardly extending member 78, to which is attached a handle 79 for raising the graphite rod 71 out of engagement with the hole 72 to permit pouring of the molten metal. Upon release of the handle 79 the weight 77 will serve to actuate the rod 70 to close the hole 72 in the crucible, stopping the pouring of the molten metal.

Referring in detail to the crucible construction 63 and the induction heating coil construction 32, a circular insulating fire brick 80 is axially mounted on the "Transite" supporting member 45 and is provided with a conical off-center hole 81 in alignment with an off-center hole 82 in the member 45. The pouring hole 72 of the crucible 63 is mounted so that the axes of the hole 72 and the holes 81 and 82 are in alignment. Referring to Figs. 5 and 6, the crucible 63 which is mounted on the insulating brick

80, is formed of graphite to withstand the high temperatures of the molten metal and is provided with a conically shaped bottom as shown in Fig. 6, which is provided with an inclined pouring groove 83, with the direction of inclination from the center of the crucible outward to the pouring hole 72. A counter bore 84 is provided for the reception of the end of the graphite rod 71. Graphite rod guards 85 are provided for shielding the rod 71 from the metal and also to provide a slot for the vertical movement of the rod. These rod guards 85 are dowelled to the side of the crucible, as illustrated at 86. Vent holes 87 are provided at the top of the crucible to permit evacuation of the crucible 63. A cover 88 is provided for the crucible 63 and has a sight hole 89 in alignment with the line of sight of the sighting device 64 in the cover of the furnace and is further provided with an opening 90 for the vertical movement of the graphite rod 71. An insulating brick 91 is positioned on top of the cover 88 and is provided with a sighting hole 92 in alignment with the hole 89 but offset with respect thereto to provide better vision of the molten metal within the crucible 63. The brick 91 is also provided with a tapered hole 93 in alignment with the hole 90 for the passage of the graphite rod 71.

25 Mounted on the support 45 and surrounding the crucible 63 and the bottom and top insulating bricks therefor is an annularly formed member 94 formed of insulating brick providing a chamber for the crucible 63. From this construction, it is evident that the metal which is 30 being melted within the crucible 63 is thoroughly insulated to provide for efficient melting of the metal and to prevent dissipation of large amounts of heat to the water cooled shell of the furnace, thus providing for longer life of the furnace. Furthermore, upon deterioration 35 and breakage of the insulating brick and crucible, these may be readily replaced. Insulating members 95 support the coil 32. These members 95 are provided with grooves 96 in which the water cooled helical induction coil 32 is positioned, insulating each coil of the construction 40 from each other and providing an effective support. The water cooled induction coil construction 32 is connected to the conductors 31 which, in turn, are suitably connected to a source of high frequency power suitable to melt the metal within the crucible 63 and raise it to 45 the temperature desired for pouring. An annular Transite plate member 97 of suitable thickness is mounted on the top of the member 95 and the insulating member 94 and is provided with a hole of sufficient diameter to permit the passage of the crucible 63 and the insulating 50 bricks 80 and 91 for replacement. The diameter of this plate member 97 is less than the inside diameter of the shell 13 to permit evacuation of the furnace and to provide room for the cooling coils 46.

In order to pour the metal, molds 18, preferably 4 in 55 number, are mounted on the rotary mold table 33 for successive rotation in and out of position underneath the pouring hole 72 of the crucible 63. Although it is preferred to pour 4 molds at a pouring, any number may be poured, depending upon the size of the molds mounted 60 on the plate 33. Upright brackets 98 have affixed thereto adjustable horizontal U-shaped members 99 for surrounding and retaining the crucibles 18 in position.

The billet mold 18 is preferably formed of graphite with an enlarged portion 101 at the top in which is 65 mounted a graphite ring member 102 provided with a hole through which the molten metal is poured and which serves to form a test egg which may be sawed off after the metal has been cooled and removed from the mold 18.

In order to provide illumination within the vacuum furnace when the metal is not up to temperature and is not 70 being poured, an electric light 103 may be provided and is preferably supported from the shell 13 by a suitable bracket construction 104.

In the operation of the vacuum casting furnace, biscuits of uranium, for example, are removed from the

bomb where originally cast and are roughly trimmed of adherent slag and blow holes by an air hammer. These biscuits must be remelted and cast into the desired shape in order to remove the slag and other impurities. This is done by removing the cover 16 from the furnace and placing into the furnace the crucible 63 in which has been placed 3 or 4 biscuits, the number and size depending upon the size of the final billet desired. The graphite crucible 63 in a preferred size is approximately 18 inches high and 12 inches in diameter with the pouring hole 72 in the bottom near one edge as described. This hole 72 is then plugged by the long graphite stopper rod 72 extending out from the top of the crucible 63 and connected as described to the rod 70. The graphite rod 71 is protected by the graphite guards 85 from breakage by the biscuits falling against it, these guards being quarter-circular strips as described, one on each side of the graphite rod 71. The crucible containing the biscuits of uranium and the furnace are then evacuated since uranium is inherently pyrophoric, and heated to about 2550° F. As the material melts most gaseous materials boil off and are evacuated, and the solid impurities rise to the top of the crucible 63 and are not poured into the molds 18. After the material is thoroughly boiled out, it is allowed to cool to 2400° F. and run into the billet molds 18 except the top slag or scum portion. The temperature may be suitably observed with optical pyrometers placed in alignment with the sighting device 64 at the top of the furnace.

The four billet molds 18 are preheated to drive off volatile material and cooled and are then placed in the furnace prior to the evacuation and heating thereof. The billet molds 18 are placed under the crucible of the induction furnace on the rotatable mold plate 33 so that they can be brought successively under the run-out hole 72 of the crucible 63. The metal is run out of the crucible 63 by lifting the graphite stopper rod 71 and allowing the metal to run into each mold 18 in turn, until each of them is filled. The size of a preferred cast billet as removed from the mold is approximately 4 $\frac{1}{16}$ inches in diameter and 16 inches in over-all length with an egg portion approximately half the diameter of the original mold and 2 $\frac{1}{2}$ inches long, leaving the resultant billet approximately 13 $\frac{1}{2}$ inches long after removal of the egg for testing. Molds for casting in which the egg is formed at the bottom may be used.

In casting the billets, particularly when uranium is cast, the formation of pipes resulting from shrinkage while cooling may be prevented by pouring the metal into the mold 18 up to about 2 inches from the top. The graphite rod 71 is then lowered, closing the pouring hole of the crucible 63 and a period of approximately two minutes is allowed to elapse depending upon the size of the mold, temperature of molten metal and cooling rate, the vacuum being maintained on the furnace during the entire casting period; and then the graphite stopper rod 71 is again raised and the mold filled while the pouring is watched through the sighting device 50. The cast billets are then allowed to remain in the furnace until they are relatively cool, remaining in the furnace approximately three hours after which the molds 18 with the billets therein may be removed by opening the closure 20 and rotating the mold table 33 with the hand wheel 38, bringing the molds 18 into position in front of the opening from which the molds 18 and the cast billets therein may be readily removed.

After a batch has been cast, the crucible 63 is refilled with a batch of metal and new billet molds 18 are placed on the billet table 33, the casting furnace sealed up, the vacuum again applied to the furnace and heat applied through the induction heating coil 32 until another batch is ready for pouring.

It is evident that a simple vacuum casting furnace has been provided for the vacuum casting of large amounts of metal so that the resultant billets are relatively free

from impurities such as slag inclusions, light metals, occluded gases, and shrinkage holes in the form of "pipes." Obviously, the resultant billets as cast have small loss in weight in view of the freedom from the above defects, and high yield from the billets when they are rolled or otherwise fabricated may be obtained.

There has also been described a novel form of vacuum casting device in which successive molds may be cast from the metal from the melting crucible, the pouring hole of the crucible suitably opened and closed with a plug actuated from the exterior of the furnace and the vacuum being maintained during the melting and casting operations.

Although this invention has been particularly described with reference to the melting and casting in vacuum of a heavy metal such as uranium, it is equally adaptable for the melting of thorium and other heavy metals where a high degree of purity is required in the resultant cast billet.

Obviously, many modifications may be made in the specific embodiment disclosed herein without departing from the intended scope of the invention. The features of the invention which are believed to be new are expressly set forth in the accompanying claims.

25 What is claimed is:

1. In a casting furnace, a shell, a mold table eccentrically arranged within said shell, said mold table including means for supporting a plurality of molds, means for rotatably supporting the mold supporting means, said 30 mold supporting means being adapted to be rotated from the exterior of said shell in which the table is located, means for cooling the mold supporting means, means for vertically adjusting the mold supporting means, a crucible above said mold-supporting means, said crucible 35 having a pouring hole eccentrically arranged in the bottom thereof, and closing means for said hole, means for opening said closing means for said hole from the outside of said shell, and means for maintaining said furnace under a vacuum during melting and casting.

40 2. A furnace for casting uranium billets comprising a shell, evacuating means, a melting crucible for the uranium, said crucible having a pouring hole in the bottom near one side, means for opening and closing the pouring hole from the outside of said shell, a rotatable table inside said shell below the melting crucible, means for adjusting said table vertically to carry molds of various heights and means for cooling said table.

3. A melting and casting furnace comprising a water-cooled shell, a removable water-cooled cover therefor 50 forming a vacuum-tight fit with the shell, a melting crucible supported in the upper portion of the shell having a pouring hole eccentrically arranged in the bottom, means for heating metal within the crucible to a molten state, rotatable means for supporting a plurality of casting molds in said shell beneath the melting crucible, means for closing the pouring hole in the crucible comprising a vertically mounted stopper rod, means for actuating the stopper rod from the exterior of said shell, a closure in said shell adjacent to the means for supporting 55 the molds whereby the molds may be mounted on the supporting means prior to casting and removed therefrom after casting, means for viewing the molten metal within the crucible, means for viewing the pouring of the metal, and means for maintaining said furnace under 60 a vacuum during the period of melting and casting.
